Specification for Design.

Patented Feb. 25, 1913.

Application filed September 23, 1911. Serial No. 651,003. Term of patent 14 years.

To all whom it may concern:

Be it known that I, HENRY E. BRYANT, a citizen of the United States, residing at Jacksonville, in the county of Duval, State of Florida, have invented a new, original, and ornamental Design for a Toy; and I do hereby declare the following to be a full, clear, and exact description of the invention, such as will enable others skilled in the art to which it appertains to make and use the same.

In the drawing: Figure 1 is a front view of the toy embodying my design, and Fig. 2 is an edge view thereof.

I claim:

The ornamental design for a toy as shown. In testimony whereof, I affix my signature, in presence of two witnesses.

HENRY E. BRYANT.
